BOOK END

Donald C. Lindley, 106 Cuba Hill Road, Greenlawn, N.Y.

Filed June 26, 1964, Ser. No. 80,596

Term of patent 7 years

(Cl. D33—3)

FIG. 1

FIG. 2

FIG. 3

FIG. 4

FIG. 5

FIG. 1 is a perspective view of a book end showing my new design;

FIG. 2 is a side elevation view;

FIG. 3 is an end elevation as viewed from the left of FIG. 2;

FIG. 4 is an end elevation as viewed from the right of FIG. 2; and

FIG. 5 is a plan view.

The side opposite FIG. 2 is substantially the same as FIG. 2 and the bottom is flat and plain.

I claim:

The ornamental design for a book end, substantially as shown and described.
